PIERCE & AUSTIN.

Signal Lantern.

No. 18,602.

Patented Nov. 10, 1857.

UNITED STATES PATENT OFFICE.

J. R. PIERCE AND L. B. AUSTIN, OF OSWEGO, NEW YORK.

SIGNAL-LANTERN.

Specification of Letters Patent No. 18,602, dated November 10, 1857.

To all whom it may concern:

Be it known that we, JOHN R. PIERCE and LEAVITT B. AUSTIN, both of the city and county of Oswego and State of New York, have invented a new and useful Improvement in Signal-Lanterns; and we do hereby declare that the same is described and represented in the following specifications and drawings.

10 To enable others skilled in the art to make and use our invention we will proceed to describe its construction and operation referring to the drawings in which the same letters indicate like parts in each of the 15 figures.

Figure 1. is a front elevation of a signal lantern the left hand half showing a section on the line *h*, Fig. 2. Fig. 2. is a plan or top view the right hand half showing a section on the line *j*, Fig. 1.

20 The nature of our invention and improvement consists in providing an extension chimney to a traversing lamp in a signal lantern having separate apartments, to prevent the smoke of the lamp from fouling the 25 glasses and obscuring the light when used in either of the apartments.

In the accompanying drawings A, is the 30 bottom of the lantern, perforated to admit air to supply the lamp, and provided with a perforated rim B, upon which the lantern stands. The bottom A, is connected to the top C, by the front bars D, D, and side plates E, E, which with the cross bars F, F, 35 form the frame of the lantern. The ears G, G, are fastened to the top C, for the bail G', by which the lantern may be suspended.

The hoop H, surrounds the perforated chimney I, and is fastened to the top C, by 40 the brackets H', so as to break the force of the wind, and prevent it from blowing into the chimney and extinguishing the lamp.

The interior of the lantern is divided into 45 three apartments, by two horizontal partitions J, J, opposite and fastened to the bars F, F; these apartments may be provided with glass of different colors so as to show light of the color required for the signal to be given. The lower apartment has trans- 50 parent glass, the middle red, and the upper green, so that the color or colors shown will depend on the position of the lamp, thus if the lamp is in the lower apartment, the light will be white, or its natural color; if in the 55 middle red, and in the upper green; and if

the lamp is placed opposite to the lower partition the light will be red and white; and if opposite the upper partition, the light will be green and red; so that with a lantern of three colors and apartments five signals may be given.

60 The top C, bottom A, front bars D, D, and cross bars F, F, are provided with flanges which form grooves to receive the edges of the glass, which may be shoved into them and secured by the moldings K, hinged to the top, bottom and cross bars, so as to close or shut over the ends of the glasses and hold them in; which moldings are fastened by the rods L, L, which pass through brackets 65 M, M, fastened to the top and bottom for that purpose.

70 To prevent the glass from being broken there are some wire bows N, N, fastened to the top bottom and cross bars as shown in 75 the drawing. The rings O, O, fastened to the sides near the upper rear corners may be used for fastening stay lines to hold the lantern in the position desired. There is a flange projecting outward on the back of 80 the lantern which is surrounded by the flange of the door P, which door is hung with hinges and provided with a sliding bolt to fasten it.

85 The horizontal partitions are perforated so as to permit the lamp and extension chimney to traverse through them. The lamp Q, sets into the cup R, which cup may be lowered into a recess in the bottom A, when the lamp is to be used in the lower apart- 90 ment.

95 The cup R, is provided with a bail S, which has two ears T, T, which traverse on the two rods U, U, fastened to the top and bottom so as to steady and guide the cup, and the lower end of the extension chimney connected to the bail of the cup by the cross V, which is fastened to the bail S, and to the lower section W, of the chimney. The extension chimney is composed of a series of 100 joints W, W, which slide into each other like the tube of a common telescope the smallest and upper joint being fastened to the top of the outer chimney, and provided with openings, one of which is shown by 105 dotted lines at X, Fig. 1, for the smoke of the lamp to pass into the outer chimney I. This extension chimney is made so long, that when the lamp is in the lower apart- 110 ment, the lower joint comes a little below

the lower partition J, so as to prevent the light from shining or the smoke from passing into the middle apartment.

The cup R, is made the same size as the 5 lower section of the chimney, so that when the lamp is in the middle or upper apartment it prevents the light from shining into the apartment below. The sections W, have a flange on the outside at their lower ends, 10 which catch under the flange on the inside of the upper end of the section next below it to hold it up when the chimney is extended; and there is a flange on the outside of the upper ends of the joints, which rests 15 on the top of the joints next below, when the sections are run into one another.

To traverse the lamp and chimney and hold them in the desired position a chain or wire cord Y, should be fastened to the bail 20 S, and passed over a sheave in the bracket Z, fastened to the top of the chimney I, and through the side of the top and hoop H, and fastened to the ring a, so, that by pulling the ring a, and hitching it under the hook 25 b, the lamp will be raised to the middle apartment. If the lamp is wanted in the upper apartment hitch the ring under the hook c; if the lamp is wanted to light both the upper and middle apartments hitch the 30 ring under the hook d.

If it is desirable to change the lamp from one apartment to another without lowering the lantern it may be done by fastening a cord to the ring a.

35 The reflectors may be made in the form shown at e, or in such other form as may be preferred and provided with a tongue to slip under the bracket f, fastened to the partitions for the two upper apartments and 40 for the lower apartment the reflector may be slipped into some pronged brackets fastened to the bottom A.

The perforated chimney I, fits onto a flange on the top e, and is fastened by a 45 horn from a spring which forces it through the flange and the top.

Some of the advantages of our invention may be enumerated as follows: 1st. A direct light is shown in all the directions required by law, and not a mere reflected light 50

as in some of the lanterns heretofore made. 2d. The light is always seen through a single thickness of glass which is of the greatest importance, particularly so with the green light which is always weak and faint. 3d. The glass is so arranged that it can be readily replaced on shipboard in a few minutes when broken. 4th. By using a single glass which is always exposed to the external air, so that it does not collect moisture, and thereby the sweating incident to double glass is avoided, which sweating is a great inconvenience requiring the glass to be removed and wiped frequently. 5th. The chimney is so arranged that the smoke 65 of the lamp always escapes without fouling the glasses. 6th. The devices for changing the light from one apartment to another are so simple that they are not likely to get out of order. 7th. The light may be changed 70 from one apartment to another so as to show signals of different colors while the lantern is aloft by a single halyard or line. 8th. The construction of this lantern is such that it gives a full side light nearly as 75 strong as the front light: and five signals may be given with glasses of three different colors.

We contemplate that skilful artisans will make such modifications of our invention, 80 as will adapt it to the purposes for which it is intended, without departing from the principles or merits of our invention.

We believe we have described and represented our improvements in signal lanterns, 85 so as to enable any person skilled in the art to make and use them.

We will now state what we desire to secure by Letters Patent to wit:

What we claim is—

The combination of a traversing chimney and lamp, so arranged as to avoid the bad effect of the lamp's smoke in signal lanterns; in the manner set forth.

JOHN R. PIERCE.
LEAVITT B. AUSTIN.
